FASTENER INSERTING MACHINE

Sylvester L. Gookin, Quincy, Mass., assignor to
 United Shoe Machinery Corporation, Borough
 of Flemington, N. J., a corporation of New
 Jersey

Application October 22, 1937, Serial No. 170,433

4 Claims. (Cl. 218—15)

This invention relates to fastener-inserting machines of the type in which fasteners such as eyelets or grommets are supplied by automatic mechanism to the mechanism for inserting them into the work. The invention is herein disclosed as embodied in a fastener-inserting machine of the type illustrated and described in United States Letters Patent No. 2,007,274, granted July 9, 1935, on application of J. A. Johnson.

Machines of the type under consideration are used chiefly for inserting large eyelets or grommets into heavy, tightly-woven fabric intended for sails, awnings, protective coverings and analogous purposes, and to insure the greatest possible security of the grommets when clenched in the fabric, the clenching tool is provided with a pointed central projection or pilot adapted to pierce or stab a fastener-receiving hole in the fabric without cutting out or removing any of the fabric. This piercing, when operating upon heavy, tightly-woven fabrics, should be completed before a fastener is brought into engagement with the work, since it is virtually impossible to obtain satisfactory results when the fastener itself is used to force the fabric onto the piercing member. For that reason the improvements set forth in the aforesaid patent provide a special mechanism by which the operation of the fastener-supplying means is postponed until the second revolution of the clutch that drives that means and the fastener-inserting mechanism. This mode of operation provides for utilizing the fastener-inserting mechanism without a fastener in the first revolution of every run to impale the fastener-receiving material on the piercing member, thereby preparing the material for insertion of a fastener in the second revolution.

Machines of the type under consideration are also sometimes used with pre-punched materials that do not require a preliminary impaling stroke, and for this reason they are provided with starting and stopping mechanism including a well-known form of one-revolution clutch and a treadle mechanism for setting it in operation, but when such machines are used according to the conditions set forth in the above-mentioned patent they have heretofore required starting and stopping twice for each fastener inserted. A well-known one-revolution clutch of the type mentioned is illustrated in United States Letters Patent No. 784,653, granted March 14, 1905, on application of O. S. Beyer, in which the elements are arranged to operate in the manner of the corresponding elements of the clutch illustrated

herein, but in which some of the details of construction are of different design.

To insure two revolutions of the driven member of the clutch for each depression of the clutch-controlling treadle, and to insure stopping the machine in every instance at the completion of the second revolution, the present invention provides improved clutch-controlling mechanism by which the clutch, once set in operation by depressing the treadle, will continue so through two revolutions, regardless of the position of the treadle, and will be automatically disengaged only during the second revolution, thereby operating the fastener-inserting mechanism twice and the fastener-supplying mechanism once in every run of the machine. The invention is illustrated as embodied in an eyelet or grommet setting machine of the type described in said Johnson Patent No. 2,007,274. It should be recognized, however, that it is capable of embodiment in fastening inserting machines of other types. Furthermore, while the clutch-controlling mechanism of the illustrated machine is such that the machine comes to rest at the end of two cycles of rotation of the driven member of its clutch, it is evident that the invention may be embodied in a mechanism designed to insure more than two revolutions before stopping, and the reference to the first and second revolution in this specification and the accompanying claims should not be taken as necessarily limiting the invention to a construction in which the clutch or the machine comes to rest at the end of the second revolution.

Referring to the drawings:

Fig. 1 is a front elevation of a fastener-inserting machine embodying the present invention;

Fig. 2 is a front elevation, partly in section, of a two-revolution mechanism including a cam for operating the raceway, a modifier, speed-reducing gearing for rendering the cam effective only during its second cycle of rotation, and a half-speed cam also driven by the speed-reducing gearing for disconnecting the clutch at the end of its second cycle of rotation;

Fig. 3 is a perspective view (direction from right-front to left-rear) including the clutch-controlling mechanism in its initial position, as when the machine is stopped;

Fig. 4 is a sectional view of the assemblage otherwise pictured in Fig. 2, taken on line IV—IV of Fig. 2;

Fig. 5 is a front elevation including the clutch, the clutch-controlling member, and connections for operating the latter, all the parts being repre-

35

45

55

sented in their initial positions, as when the machine is stopped;

Fig. 6 is a front elevation of the assemblage otherwise pictured in Fig. 3; and

5 Fig. 7 is a side elevation of a mechanism otherwise represented in Figs. 3 and 6, whereby the clutch-controlling member is automatically tripped or released to stop the machine on completion of a prescribed run.

10 Referring to Fig. 1, in which the main frame of the machine is indicated at 10, an eyelet- or grommet-inserting tool 11 of common construction is carried by a vertically movable slide 12 and co-operates with a stationary tool provided 15 with an annular clenching surface 13 and a tapered and pointed central pilot and piercing member 13 projecting upwardly from the center thereof.

The slide 12 is arranged to be reciprocated in 20 guides 16 and is operated by a wrist-pin 17 to which it is connected by a link 18. The wrist-pin is affixed to a shaft 19 journaled in bearings in the frame 10. The rear end of the shaft 19 is provided with a clutch of well-known construction 25 that operates in the manner of the clutch disclosed in the above-mentioned Beyer Patent No. 784,653. The driven member 20 of the clutch is affixed to the shaft 19, but the driving member 21 may rotate without driving the shaft except 30 when the driven member 20 is connected to the driving member 21. This member is also a flywheel and its periphery is formed to be engaged by a driving belt.

The raceway 22, surmounted by a supply-hopper 35 per 23, is arranged to present fasteners to the spring-pressed spindle 24 of the inserting tool 11. When the tool 11 is fully depressed it receives the member 14 which repels the spindle 24. The raceway and hopper unit is affixed to a frame or 40 carrier 25 and the latter is mounted on a horizontal rod 26 about which it may be oscillated by a cam hereinafter described. A roll 27 mounted on the frame 25 engages the operating cam and is maintained in contact therewith by a tension spring 28 one end of which is attached to an 45 anchoring pin 29 and the other end to a pin 30 secured to the carrier.

Referring to Figs. 2, 4, and 6, the cam 31 for operating the raceway unit is affixed to the shaft 19, and would normally operate the raceway once in each cycle of its rotation, but its operative effect is postponed until the second cycle of its rotation by a slow-speed modifier 32 arranged in concentric relation thereto and supported thereby with freedom for relative rotation. The cam 31 and the modifier are both arranged to engage the cam-roll 27, each having a concentric high portion equal in radius to the other. The modifier, because of its slow speed of 55 rotation, is effective to maintain the raceway in its retracted or inoperative position (Fig. 1) throughout every first revolution of the cam.

As pictured in Fig. 6, the modifier 32 is acting to maintain the roll 27 away from the low 60 portion of the cam 31. This figure, as well as Figs. 1, 2, and 3, represents the parts in their initial positions. A spur-gear 33 formed on the hub of the cam engages and drives an intermediate pinion 34, the teeth of which also engage 65 an internal gear 35 formed on the modifier. The pinion 34 rotates on a stationary pin or stud 36 affixed to a circular plate 37 through which the shaft 19 extends. This plate has a bearing on the shaft and also has an arm 38 by which it is 70 anchored to the stationary rod 26. The effective 75

diameter of the internal gear 35 is twice as great as that of the driving gear 33, and the modifier 32 is therefore driven at half speed to prevent operation of the raceway during the first cycle of rotation of the cam 31. It is only when the low portion of the modifier is in range of the cam-roll 27 that the cam 31 is effective to operate the raceway.

All the details of the construction, organization, and operation heretofore described are in 10 accordance with the subject-matter set forth in the aforesaid Johnson Patent No. 2,007,274, and the novel features hereinafter described provide for utilizing the slow-speed member 32 for the additional purpose of modifying the operation of 15 the one-revolution clutch to insure two revolutions thereof for each starting operation of a clutch-controlling treadle.

Referring to Figs. 3, 5, and 6, the driven member 20 of the clutch carries a rocker comprising 20 a head 40 and a stem 41 that extends through the driving member 21 but has a cylindrical bearing in the driven member 20 as exemplified in the aforesaid Beyer patent. The stem 41 is the key portion of the clutch and the portion 55 that 25 extends through the driving member 21 is of semi-cylindrical section represented in dotted lines in Fig. 6. The head 40 at one end of the stem 41 is nested in an external sectoral recess in the driven member 20, but a portion of this head 30 projects far enough from the recess to be engaged by a starting and stopping lever, 42. As shown in Fig. 5 a spring-pressed plunger 73 contained in a socket in the driven member 20 is arranged to exert force against the head 40 thereby to turn, 35 the rocker in a clockwise direction to its driving position when the lever 42 is retracted to the right to release the rocker, but when the parts are in their initial positions, as shown in this figure, the lever 42 is effective to arrest rotation of the driven member 20 and to repel the plunger 73 into its socket. Under these conditions the driven member 20 is released from the driving member 21 of the clutch because the semi-cylindrical key portion 55 of the rocker, having been 40 turned counterclockwise back to the position shown in Fig. 6, clears the driving member.

The direction of rotation of the shaft 19 is clockwise as viewed in Fig. 5 and is indicated by arrows in Figs. 1, 3, and 5. When the starting, 50 and stopping member 42 is retracted to release the head 40, a detent 43 drops over a shoulder 44 on the member 42 and remains behind the shoulder through one complete cycle of rotation of the clutch and through a portion of the second cycle to maintain the member 42 out of operation, but during the second cycle, the detent is automatically raised to release the member 42 which thereupon returns to the path of rotation of the member 40 where it is effective not only to 60 disconnect the clutch but also to arrest rotation of the driven member 20 when the parts next arrive at their initial positions.

The starting and stopping member 42 is mounted on a stationary pivot stud 45 about which it 65 may swing in a short arc. A tension spring 46 normally maintains this member in its effective or stopping position as represented in Figs. 3, 5, and 6. A starting treadle, not shown, is connected to the member 42 by operating connections 70 including a treadle-rod 47, a bell-crank lever 48, an automatic trip member 49, and a pin 50. The lever 48 is also mounted on the pivot stud 45. The pin 50 is affixed to the lever 48 but the trip member 49 is carried by the member 42 to 75

which it is connected by a pivot stud 51 and by a tension spring 52. This spring normally maintains the trip member 49 in contact with the pin 50, to the end that a shoulder 53 formed on the member 49 will cooperate with the pin 50 to impart starting movement to the member 42 and to place this member under control of the detent 43 when the treadle-rod 47 is depressed. The trip member 49 is provided with a boss 54 that is normally maintained in the path of rotation of a cam portion 65 on the driven member 23, consequently, during the first quarter of the first cycle of rotation of the driven member 23 the cam portion 65 depresses the boss 54 far enough to lift the shoulder 53 of the member 49 from the pin 50, thereby rupturing the starting connection but leaving the member 42 under the sole control of the detent 43 which has dropped behind the shoulder 44 where it is effective to maintain the member 42 in its retracted position. The clutch, therefore, continues in operation so long as the member 42 is restrained by the detent 43, but during the second cycle of rotation, the detent is displaced from the shoulder 44 to release the member 42. This releasing movement is derived from the same device (Figs. 2 and 6) that postpones the operation of the raceway until the second cycle of rotation.

For this purpose the periphery of the slow-speed modifier 32 (which, it will be remembered, makes only one revolution while the driven member 20 of the clutch and the cam 31 make two revolutions) is provided with a high portion 56 (Fig. 6) that is offset axially from the roll 27 to clear it but acts as a cam to operate a mechanism comprising a cam-roll 57 (Fig. 3), a carrier 58 therefor, a rock-shaft 60, a lever 61 affixed thereto, and a link 59 connecting the carrier 58 and the lever 61. The detent 43 is also affixed to the rock-shaft 60 and the latter is journaled in a bracket 62 affixed to the frame 10. The bracket 62 also provides support for a pivot stud 63 on which the roll-carrier 58 is mounted. A torsion spring 64 anchored to the bracket 62 applies its force to the roll-carrier 58 to maintain the roll 57 in contact with the cam member 32 and the detent 43 in its operative position.

During the second cycle of rotation of the clutch member 20, the cam portion 56 engages the roll 57 to raise the detent 43 above the shoulder

54 thereby tripping or releasing the starting and stopping member 42. The spring 46 thereupon returns the member 42 to its stopping position (Figs. 3, 5, and 6) in which it stands in the path of the head 49 where, on the completion of the 5 second cycle of rotation, the driven member 20 will be declutched and arrested. This automatic postponed tripping of the member 42 cannot be prevented by maintaining the treadle-rod 47 in its depressed position because in the first cycle of 10 rotation of the member 20, the control of the member 42 by the treadle is terminated by the action of the cam 65 on the trip-member 49.

Having thus described my invention, what I claim as new and desire to secure by Letters Patent of the United States is:

1. In a power-operated fastener-inserting machine of the type in which the driven member of a clutch drives a cam at one speed and a modifier at half-speed, the one to operate a fastener-presenting device and the other to postpone the operation of said device until the second revolution of each run of the cam; a movable starting and stopping member arranged to control said clutch, a detent arranged to restrain said starting and stopping member in position to permit the clutch to drive the machine, and means operable by said modifier in the second revolution of said cam to impart releasing movement to said detent. 20

2. A machine organized as set forth in claim 1, 30 in which said modifier is a rotary member having one portion to postpone the operation of said fastener-presenting device and another portion to impart the releasing movement to said detent.

3. A machine organized as set forth in claim 1, 35 in which the operation of said fastener-presenting device by said cam and the releasing movement imparted by said modifier are both limited to the second revolution of each run of said driven member of the clutch. 40

4. A machine organized as set forth in claim 1 but comprising also manually operable means arranged to impart starting movement to said starting and stopping member and thereby place the latter under the control of said detent, and means 45 operable by said clutch during the first revolution of said driven member to release said starting and stopping member from said manually operable means and to the sole control of said detent. 50

SYLVESTER L. GOOKIN. 50
